UNITED STATES PATENT OFFICE.

WENDELL HAUGH STILLWELL, OF TOPEKA, KANSAS.

ELECTRIC SIGNAL.

SPECIFICATION forming part of Letters Patent No. 629,624, dated July 25, 1899.

Application filed May 17, 1899. Serial No. 717,205. (No model.)

To all whom it may concern:

Be it known that I, WENDELL HAUGH STILLWELL, of Topeka, in the county of Shawnee and State of Kansas, have invented a new and Improved Electric Signal, of which the following is a full, clear, and exact description.

This invention relates to electric signaling devices adapted to be placed in a locomotive-cab or other part of a train; and the object is to provide a signal arranged in an electric circuit and adapted to be automatically closed as the train approaches a station to indicate to an engineer or to a trainman that special orders or notices may require attention and which might be overlooked or forgotten if attention were not called to them.

I will describe an electric signal embodying my invention and then point out the novel features in the appended claims.

Reference is to be had to the accompanying drawings, forming a part of this specification, in which similar characters of reference indicate corresponding parts in all the figures.

Figure 1 is a rear elevation of a portion of a locomotive-cab, showing my invention as applied thereto. Fig. 2 is a side elevation of the same. Fig. 3 is a front view of an order-holding and short-circuiting device employed. Fig. 4 is a section on the line 4 4 of Fig. 3. Fig. 5 is a section on the line 5 5 of Fig. 6, showing a circuit-closer employed. Fig. 6 is a section on the line 6 6 of Fig. 5, and Fig. 7 is a section on the line 7 7 of Fig. 6.

Referring to the drawings, 1 designates an order-holding board, here shown as arranged in the cab of a locomotive, and attached to this board is an alarm-bell 2, which alarm-bell is shown placed in a circuit comprising wires 3 4 and a battery 5. Connected to the board 1 is a spring-pressed clip 6, designed for holding papers—such, for instance, as orders or despatches—and this clip is also designed to engage with contact-points 7 8, arranged in the circuits 3 4. The object of this arrangement of parts will be hereinafter described.

Arranged within the cab is a circuit-closer comprising a spring-contact 9, having connection with the wire 3, and a spring-contact 10, having connection with the wire 4, the contact 10 being secured to a back plate 11 and the contact 9 secured to a front plate 12,

and a lever 13, pivoted to the inner side of the front plate 12, is designed to be moved between the contacts 9 and 10 to close the circuit. Attached to one end of this lever 13 is a knob 14, the stem of which extends through an arc slot 15, formed in the front plate 12, and one end of this arc slot is enlarged, so that when the knob is in the proper position the front plate may be removed or placed in position when said operation is necessary. The opposite end of the lever 13 extends into the line of vertical movement of a shifting rod 16, the plates 11 and 12 being provided each with a channel in which the rod may move and be guided.

The rod 16 extends downward through the cab and has connection with a striker-rod 17, mounted to move vertically in a hanger 18, attached to the bottom of the cab or to any other convenient part of the cab. The striker-rod 17 is held yieldingly downward by means of a spring 19, surrounding said rod and engaging at its upper end with a cross-bar in the hanger 18 and at its lower end with a collar 20 on the rod.

The lower end of the rod 17 is provided with a roller 21 of any suitable material—such, for instance, as hard rubber, vulcanite, or the like—or it may be of metal with a rubber rim. This roller 21 is designed to engage with a lifting-block 22, secured to the railway-ties at the side of the rail and at any suitable distance from a station. This block 22 is inclined downward from its center in both directions.

In operation when the roller 21 rides upon the block 22 the rod 17 will be moved upward, as will also the rod 16. The rod 16 by engaging the lever 13 will force said lever into engagement with the contacts 9 and 10, closing the circuit. Should there be no papers underneath the clip 6 or between said clip and the contacts 7 and 8, the alarm will not sound, because the current will be short-circuited by the clip 6 cutting the bell out. Should the clip, however, be insulated from the contacts 7 and 8 by means of paper upon which orders or despatches are printed, the current will pass through the bell 2, sounding the same to give an alarm, and this alarm will continue to sound until the circuit is opened by the engineer or any person moving the lever 13.

ver 13 out of engagement with the contacts 9 and 10 by pushing upward on the knob 14. Of course after the roller 21 shall have passed off the end of the block 22 the spring 19 will 5 force the rods 16 and 17 downward.

Having thus fully described my invention, I claim as new and desire to secure by Letters Patent—

1. A signaling device, comprising an electric circuit, a circuit-closer arranged in the circuit, means operated from a block at the side of a track-rail, for closing the circuit-closer, and an order-holding clip, the said order-holding clip also serving as a short-circuiting device, substantially as specified.

2. A signaling device, comprising an electric circuit, a circuit-closer arranged in the circuit and adapted to be automatically closed, an alarm in the circuit, contact-points 20 having connection with the circuit-wires, and a clip adapted for holding papers and also adapted to engage with the contact-points to

short-circuit the current and cut out the alarm, substantially as specified.

3. An electric alarm arranged in a locomotive-cab, comprising an electric circuit, an alarm in the circuit, means for short-circuiting the current, the said means also serving as a holder for papers, a cut-out in the circuit, a rod extended downward through the cab, 30 and a roller on the lower end of said rod for engaging with a block at the side of a track-rail, to force the rod upward to close the circuit-closer, substantially as specified.

4. An electric alarm, comprising an electric circuit, means for automatically closing the circuit, an alarm-bell in the circuit, and a spring-pressed clip adapted to short-circuit the current and also adapted for holding papers, substantially as specified.

WENDELL HAUGII STILLWELL.
